UNITED STATES PATENT OFFICE.

GEORGE F. WHITE, OF MIDDLETOWN, NEW YORK.

CAR-COUPING.

SPECIFICATION forming part of Letters Patent No. 349,866, dated September 28, 1886.

Application filed August 23, 1886. Serial No. 211,656. (No model.)

To all whom it may concern:

Be it known that I, GEORGE F. WHITE, a citizen of the United States, residing at Middletown, in the county of Orange and State 5 of New York, have invented a new and useful Improvement in Car-Couplings, of which the following is a specification.

My invention relates to an improvement in car-couplings; and it consists in the peculiar 10 construction and combination of devices, that will be more fully set forth hereinafter, and particularly pointed out in the claims.

In the drawings, Figure 1 is a side elevation of a car-coupling embodying my improvements. Fig. 2 is a vertical longitudinal sectional view showing the manner of coupling 15 two cars together.

A represents the draw-head, which is closed at the bottom and sides, and the upper side 20 of which is open. In the sides of the draw-head are made vertical slots B, which are connected at their upper ends by horizontal slots C. On the lower side of the draw-head, at the front end thereof, is a box, D, adapted to 25 receive the link of an ordinary pin-and-link coupling, and in the said box is a vertical opening, E, adapted to receive the usual coupling-pin. The front lower side of the draw-head is inclined, as at F, thereby forming a 30 shoulder, G.

H represents the draw-bar, which is provided at its inner end with projecting trunnions I, which enter the slots B. The said trunnions are flattened on opposite sides, whereby 35 they are adapted to enter the slots C, which are narrower than the slots B, and the flattened sides of the trunnions are arranged at right angles to the longitudinal axis of the draw-bar. The draw-bar is provided at its 40 outer end with a head, K, having converging inclines L on its upper and lower sides, thereby forming shoulders M. Immediately in rear of the head K is a transverse opening, N, which extends through the draw-bar. Near the center of the draw-bar, on the upper and lower sides thereof, are inclines O, to form shoulders P.

R represents a bail, which is pivoted to the draw-bar, and to which is attached a chain,

by means of which the outer end of the draw-bar 50 may be raised or lowered.

The operation of my invention is as follows: In order to couple two cars together provided with my form of car-coupling, the draw-bar of one car is withdrawn in the draw-head by 55 raising the trunnions in the front vertical slots B, turning the draw-bar to a vertical position, so as to cause the trunnions to enter the slots C, and then moving the trunnions rearwardly in the said slots until they reach 60 the rear vertical slots B and drop therein. The head of this draw-bar will then have its shoulders M directly in line with the shoulder G of the draw-head. When the cars come together, the inclined head of the opposite 65 car will strike against the inclines F and L, thereby raising the head of the draw-bar, and permitting the head of the opposite draw-bar to enter the draw-head and cause its shoulders M to be engaged behind the shoulders G 70 and M, as illustrated in Fig. 2, thus automatically coupling the cars together. In order to uncouple the cars it is only necessary to raise the outer end of one of the draw-bars. Another way to couple the cars is to permit 75 both the draw-bars to project from the outer end of the draw-head, and when the cars come together the head of one draw-bar will pass under the other and become engaged by the shoulders G and P, and the draw-bar on top 80 will have its shoulders in engagement with those of the under draw-bar.

When a car provided with my form of coupling is to be coupled to a car by means of the usual pin-and-link coupling, this may be accomplished by directing the link into the box D and dropping the pin in the opening E, so as to engage the link, as will be very readily understood.

Having thus described my invention, I 90 claim—

1. The combination, in a car-coupling, of the draw-head, and the draw-bar pivoted therein and having the inclines L and O, thereby forming the shoulders M and P at the outer end 95 and at the center of the draw-bar, for the purpose set forth, substantially as described.

2. The combination of the draw-head hav-

ing the incline F at its front end and the vertical slots B in its sides connected by the horizontal slots C, and the draw-bar having the trunnions adapted to enter the slots and pivot 5 the inner end of the draw-bar to the draw-head, the said draw-bar having the inclines L at its outer end, and the shoulders M, for the purpose set forth, substantially as described.

In testimony that I claim the foregoing as my own I have hereto affixed my signature in the presence of two witnesses.

GEORGE F. WHITE.
